UNITED STATES PATENT OFFICE.

JOHN J. KOCHER, OF LOS ANGELES, CALIFORNIA.

COMBINED SHAFT-COUPING AND ANTIRATTLER.

SPECIFICATION forming part of Letters Patent No. 674,444, dated May 21, 1901.

Application filed September 18, 1900. Serial No. 30,417. (No model.)

To all whom it may concern:

Be it known that I, JOHN J. KOCHER, a citizen of the United States, residing at Los Angeles, in the county of Los Angeles and State 5 of California, (with post-office address at 219 West Fifth street, in said city,) have invented certain new and useful Improvements in a Combined Shaft-Coupler and Antirattler, of which the following is a full, clear, and exact 10 description, reference being had to the accompanying drawings, which form a part of this specification.

My invention relates to certain new and useful improvements in a combined shaft-coupling and antirattler; and my invention consists in certain features of novelty hereinafter 15 described and claimed.

Figure I is a top view of my improved device. Fig. II is a longitudinal section taken 20 on line II II, Fig. 1. Fig. III is a detail top view of a shaft-iron. Fig. IV is a perspective of a coupling, showing the same open. Fig. V is a side elevation of the coupling, showing it closed.

25 Referring to the drawings, 1 represents an axle, and 2 a clip for securing the coupling to the axle, said clip 2 having the usual screw-threaded lower end 3, with nuts 4 and clip-plate 5 in position.

30 6 represents the lower jaw of the coupling, which is preferably an integral part of the clip 2 and is provided at its forward end with a lip 7, forming a concave seat 8.

35 9 represents a shaft-iron, having a yoke 10, the outer ends of said yoke being connected with a coupling - pin 11, surrounded by a washer 12, the washer being preferably made of some material adapted to yield under pressure.

40 13 represents a stirrup adapted to straddle the body of the lower jaw, as shown at 14, it being movably secured to the same, so as to move both up and down and backward and forward. On the upper end of the stirrup 13 is a jaw 15, having an overhanging lip 16 with an under concave seat 17.

45 18 represents a locking-head, somewhat anchor-shaped and having a stem 19, one end of said stem being pivoted at 20 to the lower end 50 of the stirrup 13 and having its ends squared, as shown at 21, for receiving a wrench 22.

In forming the coupling the shaft-iron 9 is

brought into position so that the bolt 11, with its surrounding washer 12, is placed within the seat 8 of the lower jaw 6. (See Figs. III 55 and IV.) After the shaft-iron is in position the upper jaw 15 is pressed down upon the coupling-bolt, as shown in Fig. V. When the wrench is applied to the squared end 21 of the locking-head 18 and said head is turned up 60 into position, (shown in Figs. II and V,) the convex face 23 of the locking-head 18 engages a concave face 24 on the under side of the lower jaw 6, the surface of said face gradually approaching the pivot-pin 20, so as to 65 form a clamp that tightens the upper coupling down upon the lower coupling, thus taking up any lost motion or wear between the respective jaws.

25 represents an upwardly-extending heel 70 at the back of the head 18, which, together with the convex face, forms a double bearing for the coupling-head.

26 represents a shoulder on the stem of the lower jaw 6, said shoulder limiting the backward movement of the lower end of the stirrup 13.

I claim as my invention—

1. A combined shaft-coupling and antirattler comprising a lower jaw having means for 80 securing it to an axle and formed with a lip having a concave seat, a shaft-iron formed with a yoke having a coupling-pin and washer, a stirrup adapted to straddle the body of the lower jaw and formed, at its upper end, with 85 an overhanging lip having a concave seat, and means for locking the stirrup to the lower jaw.

2. A combined shaft-coupling and antirattler comprising a lower jaw having means for securing it to an axle and formed with a lip 90 having a concave seat, and with a concave surface on its under side, a shaft-iron formed with a yoke having a coupling-pin, a stirrup adapted to straddle the body of the lower jaw and formed, at its upper end, with an overhanging lip having a concave seat, and a locking-head having a stem pivoted to the lower end of the stirrup and formed with a convex face and a heel. 95

JOHN J. KOCHER.
